UNITED STATES PATENT OFFICE

WILLIAM F. A. BUEHNER, OF MIAMI, FLORIDA, ASSIGNOR, BY MESNE ASSIGNMENTS,
TO OUTBOARD MOTORS CORPORATION, A CORPORATION OF MICHIGAN

OUTBOARD MOTOR

Application filed December 17, 1927. Serial No. 240,868.

My present invention relates to improvements in outboard motors, and particularly to propeller drive and cooling water pump mechanism therefor.

5 An object of this invention is to provide a mechanism which is simple and inexpensive to manufacture, is readily assembled and disassembled, and which will not be likely to be broken or otherwise rendered inoperative under ordinary conditions of use.

10 A further object resides in so constructing the parts that a constant supply of cooling water will be maintained at all times during operation of the engine and under all conditions of use.

15 Another object resides in providing a pump mechanism which is readily fitted in place and is easily removed for installation of a new pump or replacement of any of the parts, 20 should this become necessary for any reason.

25 Yet another object is to provide for a slight yielding of the propeller to thus avoid breakage of the propeller blades or damage to the driving and power connections, in case the propeller should strike a submerged log or other obstruction.

With the above and other objects in view, which will be apparent to those skilled in the art, this invention includes certain novel features of construction and combinations of parts which will be set forth in connection with the drawings.

In the drawings:

Figure 1 is a view in side elevation showing my improved structure.

Fig. 2 is a longitudinal vertical sectional view through the structure.

Fig. 3 is a horizontal sectional view taken substantially on line 3-3 of Fig. 1.

40 Fig. 4 is a view in perspective showing the pump casing.

Fig. 5 is a perspective view to better show the propeller drive spring.

45 My present invention is adaptable for use with substantially all types of outboard motors as the same are now constructed, and might be fitted as factory equipment, or can be manufactured to be sold separately and to be fitted individually to several of the present 50 types of motors as replacement for the present

propeller drive and cooling water pump mechanism thereof.

In the present instance I have illustrated my invention in connection with a standard form of drive shaft 1 and tubular drive shaft 2, and it will be understood that these parts can be varied to take other standard forms and that any desired and suitable type of motor unit and boat mounting therefor can be employed.

60 A housing 3 is adapted to have the propeller shaft 4 journalled therein and is provided with an opening 5 to receive the lower end of drive shaft 1. This housing 3 serves as a propeller mechanism and pump housing, 65 and this housing 3 is secured upon the tubular housing 2 by means of the connection housing 6. In horizontal section the housings 3 and 6 are shaped to be substantially stream-lined, 70 as best shown in Fig. 3, so that the least possible obstruction to passage through the water will be offered.

The lower part of housing 3 is cored out as at 7 to provide a gear case and the propeller shaft 4 is journalled in this space, 75 preferably in roller bearings 8 and 9 carried by the closure cap 10 and adjustable bearing plug 11 respectively. Cap 10 closes the gear case to exclude water and confine grease or other lubricant, and bearing plug 11 can be 80 adjusted to compensate for wear and to insure a proper mounting of shaft 4. Shaft 4 has the usual bevel or miter gear 12 keyed, pinned or otherwise secured thereon, and the usual bevel or miter gear 13 is pinned, keyed 85 or otherwise secured on the end of drive shaft 1 to be enmeshed with gear 12.

90 The opening 5 is substantially circular in cross section and is of a diameter considerably larger than would be required for shaft 1, this opening 5 being designed to take and hold the pump case 14. The pump case is made substantially tubular in form with the upper end open and the lower end closed but provided with a central opening 15 through 95 which power shaft 1 passes. A suitable gland and stuffing box structure is provided at 16 to give a packed joint around the shaft 1.

95 A passageway 17 is provided between opening 5 and the gear case opening 7 of sufficient 100

- size to permit free passage of the gear wheel 13 when the same is pinned or otherwise secured upon drive shaft 1, and yet a shoulder 18 is provided to support the pump case 14.
- 8 An annular recess 19 is provided at the upper end of housing 3 around the opening 5 and a closure member 20 adapted to fit within the upper end of pump case 14 has a flange 21 which is received in this annular recess.
- 10 The closure member 20 is provided with a bearing sleeve 22 adapted to fit up within the tubular housing 2 to form a journal bearing for power shaft 1, and a suitable gland or stuffing box is provided at 23 to give a packed joint around the power shaft.
- 15 Housing 3 has a water inlet bore 24 formed preferably substantially vertically in the forward part thereof with intake passages 25 opening through the sides. A tubular screen or strainer 26 is fitted in this inlet bore 24 and water passing through intake passages 25 is thus strained and freed from floating sticks, weeds, or other matter which might clog the cooling water system. A lateral passage 27 establishes communication between the pump case opening 5 and water intake bore 24, and an opening 28 connects the lateral passage 27 with the interior of the pump case 14 near the bottom thereof. A key 29, or any other suitable form and type of locating and securing means, will be provided to insure proper registry of opening 28 with passage 27 when the pump case is slipped into place.
- 25 A spiral water impeller 30 is keyed or otherwise secured upon the power shaft 1 within pump case 14 and this impeller screw has the spiral vane 31 thereof inclined to raise water within the case 14 when the power shaft 1 is turned in the normal direction of rotation of the motor power plant. Closure member 20 has a screw threaded opening 32 therethrough and a water supply pipe 33 connected in this opening 32 extends up through the tubular housing 2 or is otherwise led to a point to be conveniently connected with the water jacketed cylinders of the motor.
- 40 In assembling the structure the impeller screw 31 is secured upon power shaft 1 after bearing portion 23 has been fitted in place, and pump case 14 is then placed over the spiral impeller to fit upon the closure member 20, following which gear 13 is fitted and secured in place. This entire assembly is then inserted through passage or opening 5 and when pump case 14 comes to a proper bearing against shoulders 18 miter gear 13 will be in proper mesh with gear 12 and flange 21 will be received in recess 19. The tubular housing 2 has a flange 34 formed on the lower end thereof to fit within an annular recess 35 on the lower side of connection housing 6, and the housings 3 and 6 are provided with aligned openings to receive screws 36, or other suitable fastenings, by which the connection hous-

ing is drawn down against and is securely clamped to the upper end of the housing 3. This connection and mounting closes the upper end of intake bore 24, secures pump case 14 and closure member 20 in place and 70 clamps the parts securely upon the lower end of the tubular housing 2 by which this structure is supported and carried. If desired, a roller or ball bearing can be provided at 37 around power shaft 1 adjacent the bearing 75 portion 23.

With the parts assembled as set forth operation of the motor will rotate power shaft, which will turn the propeller through the gear connection; and, at the same time the 80 impeller spiral or screw 30 will be revolved in the pump case to lift water from the intake opening 28 and force this water up through the water supply tube 33 to properly cool the engine or motor. In disassembling the parts it is only necessary to remove the screws or other fastenings 36 and the various portions can then be readily taken apart in the reverse order of their assembly.

85 A splash plate 38 is cast integral with or is otherwise formed to be carried by the connection housing 6 to be disposed to overlie the propeller, and with this construction it will only be necessary to replace the connection housing 6, should the splash plate be 95 broken, bent or otherwise rendered unsuitable for use.

90 The propeller 39, which is of any desired design, type and pitch to suit the particular requirements of use, has the hub 40 thereof somewhat elongated and fitted to be capable of turning movement on the end of the propeller shaft 4. A nut 41, or other suitable fastening, is provided to hold the propeller in place, but does not clamp or secure the same against turning. A recess 42 is provided at the inner end of the hub 40 and at the inner end of the recess 42 a notch 43 is formed. The propeller shaft 4 has a bore or opening 44 formed therein at a point spaced from the location of the notch 43 and a spiral spring 45 fitted around the propeller shaft within the recess 42 has its ends 46 and 47 bent outwardly and inwardly to fit the notch 43 and the opening 44. The spring 105 is formed or wound to expand when twisted in a direction corresponding to the direction of propeller shaft 4 and the material thereof is of a tension to normally be unaffected by the ordinary working pressure upon propeller 39. Thus, the propeller is connected with the propeller shaft in a substantially fixed relation under normal working conditions; however, if the propeller strikes an 110 obstruction or should become fouled, or the rotation thereof is otherwise interfered with the increased pressure upon the propeller will cause spring 45 to flex and yielding movement between the propeller and shaft 4 is thus 115 allowed to prevent breaking of the propeller,

120

125

130

stripping of the gears, or damage to other parts of the structure. The usual strut 48 can be provided as an additional safeguard for the propeller.

5 From the foregoing it will be seen that I have provided a structure with which the propeller driving and pump mechanisms are very readily and expeditiously assembled and disassembled, with which a constant supply 10 of cooling water is maintained under pressure during the operation of the motor, and further that the parts are very effectively guarded and cushioned against the danger of breakage or damage.

15 While I have herein shown and described only certain specific embodiments, mountings and connections of the various features of my invention, it will be appreciated that changes and variations can be made, almost 20 without number, to suit varying conditions of installation and use without departing from the spirit and scope of my invention.

I claim:

25 1. An outboard motor structure having a downwardly extending power shaft encased by a supporting housing, a connecting housing mounted on the supporting housing, a pump and propeller housing removably connected to the connecting housing and provided with an opening to receive a pump and 30 an inlet passage communicating therewith, and a pump mechanism to be assembled on the power shaft and removably fitted as a unit within the pump housing when the 35 mounting housing is detached.

2. An outboard motor structure having a power shaft driven by a water cooled engine, a power shaft housing, a pump and propeller housing carried by said power shaft housing and provided with a cooling water 40 inlet, said pump housing being provided with a pump receiving opening around the power shaft, a separate pump case removably fitted in said opening, an impeller connected on the 45 power shaft to rotate within said pump case, and an outlet connection from the pump case to the cooling jackets of the engine.

3. A water cooling system for outboard motors including a sectional casing forming 50 a housing for a drive shaft and also a housing for propeller drive gearing, releasable means for securing said sections together, one of said sections having an opening surrounding said drive shaft, a separate pump 55 casing removably fitted in said opening and held in position therein by the action of said releasable fastening means and the sections secured together thereby, and an impeller fixed to said drive shaft and operating in 60 said pump case, there being an inlet to said pump case and an outlet leading from the pump case to the water cooling system.

In testimony whereof I hereunto affix my signature.

65 WILLIAM F. A. BUEHNER.
